SIGURD RUMP, OF BOSTON, MASSACHUSETTS, ASSIGNOR TO AMERICAN BROWN
BOVERI ELECTRIC CORPORATION, OF NEW YORK, N. Y., A CORPORATION

DEVICE FOR DETERMINING THE CONDITION OF TRANSFORMERS

Application filed March 2, 1926. Serial No. 91,768.

In operating transformers of large output it is important that internal damages, which may occur, and which are generally invisible, and therefore are not noticed for long periods 5 of time, may be determined as early as possible in order that they may be removed. Such damages, especially short circuits between core laminations and other defects in insulation, increase in time and lead to sudden 10 serious overheating and burning, sometimes to fire and to complete uselessness of the whole apparatus.

Successful use has been made of the gas development which is due to local heating and 15 forming of arcs on the damaged part in order to determine defects. Such gas development, however, occurs only when the heating is sufficient to evaporate or decompose a certain amount of oil.

20 The present arrangement for protection, however, acts earlier and indicates the defect in a station where a gas development has not started. The method is based on the invariable appearance of watt losses in a damaged 25 part. Such losses must certainly be balanced by the network and they are always balanced only by one side, that is, either by the high tension side or by the low tension side of the transformer. The current of both transformer sides compared and referred to a ratio of 30 transformation 1, results normally in a differential current which is equal to a certain watt loss, namely, the iron loss plus copper loss, which is caused by the magnetizable current. 35 This watt loss is constant as long as the primary voltage of the transformer is constant, therefore, the differential current equals the watt loss. The differential current or differential output has already been used for indicating defects in transformers as well as for 40 operating safety devices as soon as such current or output exceed their normal values. Each watt consumption resulting from any 45 losses can, theoretically, be replaced by a resistance which would cause the same losses. Such theoretically compensation resistance—although practically not present—can be measured with an ohmmeter. According to 50 the invention, an ohmmeter really will there-

fore be used for indicating a transformer defect.

The drawing diagrammatically shows one application form of the invention. *a* indicates the low tension winding and *b* the high tension winding of the transformer to be protected. On both sides are connected current transformers *c* and *d*, the secondary windings of which are connected in opposition and are arranged in the circuit of an 55 ohmmeter *e*, which is constructed in accordance with the cross coil principle. The stationary coil *f* and coil *g* of the movable system, which are connected in series, are traversed by the differential current. Coil *h* 60 of the movable relay system lies at a constant angle to coil *g* and is fed by the voltage transformer *i*, the primary coil of which is connected to the low tension side of the transformer. By the action of the ohmmeter 70 arm *m* connected to the movable system, a contact *k* of an auxiliary circuit, diagrammatically shown in the drawing, is operated, which auxiliary circuit contains the indicating, alarm or protection apparatus. 75

It will be understood from the foregoing that the movable system of ohmmeter *e* comprises coils *g* and *h* and the arm *m*, these parts being fixedly connected together to move as a unit with relation to coil *f*. 80

The ohmmeter is so constructed that the arm *m* operates contact *k* in the event the compensation resistance increases a certain amount over the normal no-load losses of the transformer. Therefore the connections 85 can be adjusted so that the arrangement will be sensitive to a very small excess over the allowable losses.

It is obvious that the protective apparatus is actuated by all damage inside the transformer, therefore, especially by short circuits in windings and similar defects where the apparatus causes the disconnection of the defective transformer. The apparatus can also be so arranged in the known manner that its 90 operating time depends on the magnitude of the resistance. 95

The new arrangement may also be made with certain modifications for protection of other apparatus and electric machines. At 100

all events, it can be used wherever internal damage causes a change of the resistance value of the winding to be protected.

I claim:

1. The combination of a transformer having primary and secondary lead connections, of a protective system therefor comprising a pair of differentially-connected transformer windings associated with the primary and secondary lead connections, and a relay device in series with said differential transformers energized by the differential effect of the currents of said windings to operate only in response to the variations of the watt component of said differential current.
2. In electrical protective systems for transformers comprising a pair of serially connected transformer windings, differentially energized by the primary and secondary currents of the transformer to be protected, a relay device having a pair of movable coils fixedly connected and a stationary coil cooperating therewith, one of said movable coils and said stationary coil being connected in series with said serially-connected transformer windings, the other of said movable coils being energized by a current proportional to the voltage across the transformer to be protected to actuate said relay in response to the watt component of the differential current in said serially-connected transformer windings.
3. In a protective system, a transformer having primary lead connections and secondary lead connections, a current transformer in the primary lead connections, a current transformer in the secondary lead connections, an ohm-meter relay comprising a stationary coil and a pair of movable coils, and said movable coils being fixedly connected and differentially actuated by said stationary coil, the secondary windings of said current transformers being differentially connected in series with the serially connected stationary coil and one movable coil of said relay, the other of said movable coils being supplied from across said transformer.
4. In a protective system, a main transformer, a pair of secondary transformers respectively connected to the windings of said main transformer, the secondary windings of said secondary transformers being differentially connected in series, an ohmmeter in series with said differentially connected transformers, and a transformer connected across the primary of said main transformer, the secondary of said last mentioned transformer being connected in series with the voltage coil of said ohmmeter.

In testimony whereof I hereunto sign my name.

SIGURD RUMP.
